US00D926396S

(12) **United States Design Patent** (10) **Patent No.:** **US D926,396 S**
(45) **Date of Patent:** **** Jul. 27, 2021**

(54) **STOP BARKING DEVICE**

- (71) Applicant: **Shenzhen Smart Pet Technology Co., Ltd**, Shenzhen (CN)
- (72) Inventor: **Yaya Jia**, Shenzhen (CN)
- (73) Assignee: **Shenzhen Smart Pet Technology Co., Ltd**, Shenzhen (CN)

(**) Term: **15 Years**

(21) Appl. No.: **29/775,291**

(22) Filed: **Mar. 23, 2021**

(51) LOC (13) Cl. **30-99**
(52) U.S. Cl. **USPC D30/199; D10/104.1**

CLAIM

The ornamental design for stop barking device, as shown and described.

DESCRIPTION

FIG. 1 is a perspective view of a stop barking device showing my new design;

FIG. 2 is another perspective view thereof;

FIG. 3 is a front view thereof;

FIG. 4 is a rear view thereof;

FIG. 5 is a bottom plan view thereof;

FIG. 6 is a top plan view thereof;

FIG. 7 is a left side view thereof; and,

FIG. 8 is a right side view thereof.

The broken lines depict portions of the stop barking device and form no part of the claimed design.

1 Claim, 8 Drawing Sheets
